PRINTER-PROCESSOR FOR PHOTOGRAPHIC FILM

Donald F. Blazek, Bensonville, Ill., assignor to Chicago
Aerial Industries, Inc., a corporation of Delaware

Filed Nov. 30, 1965, Ser. No. 88,260

Term of patent 14 years

(Cl. D61—1)

The essential features of my design are shown in full lines in the drawings.

I claim:

The ornamental design for a printer-processor for photographic film, as shown and described.
